UNITED STATES PATENT OFFICE

1,953,661

SAFETY GAS BURNER AND VALVE

Joseph Svaicer, Chicago, Ill.

Application May 29, 1930, Serial No. 456,836

7 Claims. (Cl. 158—117.1)

This invention relates to a gas burner or rosette and more particularly to an auxiliary burner attached thereto and also to the provision of an automatic valve cooperable with said auxiliary burner. It is well known that each year many deaths are caused by asphyxiation due to accidental extinguishment of a gas flame, usually that of an ordinary gas stove because of substantial or partial obstruction of the gas jet openings of such stove. My invention has for its purpose the provision of means for eliminating the danger stated and which frequently recurs whenever a vessel overboils when being heated over a gas flame.

An important object of my invention is the provision of a device attachable to a conventional gas burner which is adapted to emit a comparatively large gas flame when the flames of the gas rosette are partially or totally obstructed accidentally or are accidentally extinguished in order to release means normally holding the gas entrance valve in open position.

A further important object of the invention is the provision of a spring pressed gas inlet valve and means attached thereto which normally hold the inlet valve in open position but which release said valve when heat is applied thereto.

A further object of the invention is the provision of an auxiliary burner comprising a housing having an inlet communicating with the gas source and two outlets, each of which normally emit a small flame, said auxiliary burner being adapted to emit a comparatively large flame when the main gas burner flames are extinguished without a closure of the gas inlet.

A further important object of my invention is the provision of a gas burner for gas stoves comprising a main gas rosette, an auxiliary burner disposed upon and communicating with the interior of the main inlet pipe, and a self-closing gas inlet valve adapted to be released from normal open position by emission of a large flame by said auxiliary burner.

Other and further important objects of this invention will be apparent from the disclosures in the specification and the accompanying drawing.

This invention (in a preferred form) is illustrated in the drawing and hereinafter more fully described.

On the drawing:

Fig. 1 is a top plan view of a conventional gas rosette, inlet pipe and its bell-shaped mouth, and showing my auxiliary safety burner and valve control means.

Fig. 2 is a cross-sectional side view in elevation showing the inlet valve, the inlet valve control and the auxiliary burner disposed adjacent the bell-shaped mouth of the gas inlet.

Fig. 3 is a view of my auxiliary burner taken 60 from the bottom.

Fig. 4 is a side elevation, in cross section, of my self-closing valve and the control means therefor.

Fig. 5 is a view taken from the left of Fig. 1 65 and showing the gas inlet valve and closure plate from the inside.

As shown on the drawing:

The reference numeral 1 indicates a gas burner of conventional rosette form having petal-like 70 portions 2, only part of which are shown in Fig. 1 to form a rosette. Said gas burner 1 comprises a reduced gas inlet portion 3 and an enlarged mouth portion 4 of the usual bell-shaped form. The bell-shaped mouth 4 has a slender opening 75 5 extending from its enlarged portion to the reduced portion 3 of the gas inlet. Within the gas inlet portion 3 is a nozzle 6 pointing in the direction of the rosette burner, said nozzle 6 forming a by-pass for the incoming gas, the purpose of 80 which will appear hereinafter. As is well known, the gas burner or jet openings become obstructed either totally or partially through overboiling of liquids which are spilled upon the gas jet openings, and this has caused numerous fatal accidents 85 due to escapement of gas through the jet openings or parts thereof which, though obstructed by liquid, are sufficiently open to permit subsequent escape of gas.

An auxiliary burner 7 comprising a slender 90 housing, a gas inlet pipe 8 integral therewith, a peripheral downwardly flaring flange 9 and an inverted spout 10 is held disposed adjacent the by-pass of inlet pipe 3 by threaded engagement of the gas inlet pipe 8 with the threaded aperture (not shown) in the wall of inlet pipe 3, as shown in Fig. 2. Said auxiliary burner 7 has a gas outlet 11 pointed in the direction of the rosette burner and an inner rear gas outlet 12 opening to the inside surface of the downwardly 95 flaring flange 9. An aperture 13 is formed in the flange 9 at a point nearest the gas rosette. The auxiliary burner is made of such dimension so that the inverted spout 10 lies directly over the opening 5 in the bell-shaped mouth portion 4 105 and the opposite end thereof is a short distance from the nearest flame of the gas rosette. The gas inlet pipe 8 extends downwardly preferably at one side of the auxiliary burner 7 so that it will not obstruct ignition and the gas flame beneath 110

the auxiliary burner, as will be explained herein-after.

The mouth 4 of the gas burner 1 is closed by a double-walled closure plate 14 which carries 5 turned edges 15 adapted to hook over flange 16 on the mouth portion 4 to secure said plate 14 thereto. The closure plate 14 has adjustable air inlet openings 17 thru which air is drawn to the gas entering the burners. Thru the central opening in the closure plate 14 is a short tube 18 which has internal threads and an enlarged head portion 19, the latter permitting convenient attachment thereof to the conventional nozzle of a gas supply pipe.

15 Disposed within a second aperture in the closure plate 14 and adjacent the opening of tube 18 is a ring 20 having a projecting stud 21 which is preferably grooved for the reception of a small ring. To the inner side of closure plate 14 is 20 secured an annular metal housing 22 for the purpose of protecting a coil spring 23 therein.

A clamp 24 encircles the pipe 18 and is held thereon by a screw 25, said clamp having a pin 26 passing thru its upper portion and which 25 also passes thru the aperture of stopper valve 27 and serves as a fulcrum therefor. The stopper valve 27 is arcular in shape and has a flat inner face which carries a round integral abutment adapted to snugly seat into the opening of tube 18 30 to close the same.

Slidably mounted within ring 20, housing 22 and spring 23 is a connecting link 28 of metal or the like which carries an annular flange adapted to bear against the end of spring 23. Said connecting link 28 has a bifurcated end which is pivoted to the upper portion of the stopper valve 27 by means of a pin passing thru said bifurcated end and thru an aperture in the stopper valve 27. The opposite end of connecting link 28 is pivoted 40 to a short lever 29, as shown in Fig. 4, which said lever is adapted to be moved to right angled position to the connecting link 28 and fulcrums on the shoulder of metal ring 20 in order to hold the connecting link 28 against the action of coil spring 45 23, thereby normally holding the stopper valve 27 in open position. Lever 29 is normally held in its upward valve opening position and adjacent stud 21 (as shown in Fig. 2), by means of a ring 30 of highly inflammable material.

50 The operation is as follows:

It will be apparent that due to the pressure of the source of gas which enters nozzle 6 quickly a constant pressure of gas is maintained through restricted openings within the rosette burner although gas is constantly flowing to the ignited flames above the rosette. This reduced pressure causes gas to flow from within the rosette into the space between nozzle 6 and the wall of the gas inlet 3 and into inlet pipe 8, auxiliary burner 63 7 and escape through outlets 11 and 12 of said burner. As soon as gas begins escaping from the outlet 11 and due to the proximity of said outlet to the flames of the gas rosette, such gas escaping from outlet 11 is ignited and a small flame will be 65 maintained thereat. During the interval that this last mentioned ignition has been brought about a portion of the gas which enters the pipe 8 flows through the U-shaped tunnel therein and escapes at outlet 12, and due to the buoyancy of 70 the gas fills the space within the downwardly extending annular flange 9 and then "overflows" said gas rising due to its buoyancy.

This gas which so rises is immediately ignited 75 from the flame burning at opening 11 and due to the constant but restricted flow of gas through

outlet 12 a flame will remain burning at 12. This status is maintained constantly during normal consumption of gas by the flames of the gas rosette.

If the flames of the gas rosette are extinguished through obstruction of the rosette burner orifices the draft or pull on the gas within the gas rosette is considerably reduced as is well known, thereby resulting in a greater pressure of gas within the gas rosette, such greater pressure causing a considerably larger volume of gas to be forced through the restricted openings in the burner 7. This increased pressure also forces a large volume of mixed gas and air through slot 5, a portion of which flows within the space surrounded by the flange 9 of burner 7 where it is immediately ignited by the flame at 12. Thereupon the entire space beneath and within the burner 7 and above said slot is constantly ablaze due to the inflow of gas and air through slot 5 and through the restricted openings in the burner 7. This flame is of sufficient size that a portion thereof, particularly that portion above the slot 5, burns the inflammable ring 30, thereby permitting the spring pressed stopper valve 27 to close quickly. After 100 closure of the valve 27 the small amount of gas within the gas inlet pipe which has passed the valve is consumed and the flames above the slot 5 and about said auxiliary burner are extinguished.

In the operation of applicant's device accidental extinguishment of a gas rosette occurs in practically all cases by overflow of water, coffee, soup or the like from a container. Particles of the liquid food, whether it be water or other matter, always remain in the small holes of the gas rosette, thereby either partially or wholly obstructing the further flow of gas through the holes of said burner. The result is that due to the influx of the gas under pressure, the pressure in 115 the elongated inlet pipe formed integral with the usual gas rosette will be increased. Because the holes of the main gas rosette are wholly or partially obstructed by the liquid any gas which may continue to flow through the apertures of the 120 main gas rosette will not be reignited by the flames of the auxiliary burner.

I am aware that many changes may be made and numerous details of construction may be varied thru a wide range without departing from 125 the principles of this invention, and I therefore do not purpose limiting the patent granted thereon otherwise than necessitated by the prior art.

I claim as my invention:

1. In combination, a rosette having a plurality 130 of gas jet openings, an inlet pipe having a side opening therein and connecting said rosette with a gas source; a valve in said inlet pipe; a spring tending to close said valve; an inflammable link engaging said valve to hold the same in open position, obstruction of said gas jet openings operating to cause emission of gas and air through said side opening; and an auxiliary burner mounted between said rosette and said side opening and communicating with the gas source, the 140 flames of said auxiliary burner being positioned to ignite the gas when emitted from said opening to destroy said link to permit said spring to close said valve.

2. In combination, a rosette having a plurality 145 of gas jet openings, an inlet pipe having a slotted opening therein; a valve in said inlet pipe for controlling the gas supply; a spring tending to close said valve; an inflammable link engaging said valve and for holding the same in open posi- 150

- tion, the obstruction of said gas jet openings operating to cause emission of gas and air thru said slotted opening; and an auxiliary burner mounted between the main burner and said opening and 5 communicating with the gas supply, said auxiliary burner being positioned to ignite the gas and air emitted from said opening to destroy said link to effect closing of said valve.
3. A device of the class described comprising 10 a rosette having a plurality of gas jet openings, an inlet pipe having a side opening therein and connecting said rosette with a gas source; a valve in said inlet pipe; a spring tending to close said valve; an inflammable link engaging said valve to hold the same in open position, obstruction 15 of said gas jet openings operating to cause emission of gas and air through said side opening; and an auxiliary burner having fuel outlet openings therein and mounted between said 20 rosette and said side opening, the fuel emitted from said auxiliary burner being ignitable from the flame of said rosette and being adapted to ignite the fuel emitted from said side opening to destroy said link.
- 25 4. In combination, a gas burner having a fuel outlet opening; a fuel inlet pipe connecting said burner and a fuel supply, said inlet pipe having a side opening therein; a valve in said pipe; a spring tending to close said valve; an inflammable link 30 engaging said valve to hold the same in open position, obstruction of said burner jet openings operating to cause emission of fuel from said side opening; and an auxiliary burner mounted between said first mentioned burner and said opening 35 and communicating with the fuel supply and having openings therein, the fuel emitted from said openings being ignitable from said first mentioned burner, the flames of said auxiliary burner operating to ignite the gas fuel when emitted 40 from said side opening to cause destruction of said link to effect closing of said valve.
- 45 5. In combination with a gas burner having fuel outlet openings, a pipe for connecting said gas burner with a gas source, said pipe having a side outlet port; an auxiliary burner mounted adjacent to said gas burner and communicating with the gas source and comprising an elongated body having a downwardly extending periphery and having gas outlet ports therein, one of said 50
- outlet ports being adjacent the first mentioned gas burner fuel outlet openings and ignitable from the flames thereof and normally emitting a flame when said first mentioned gas burner is ignited; a gas inlet valve controlling the gas supply; a spring engaging said valve tending to close the same; an inflammable link adjacent said side outlet port and engaging said valve to hold the same open, the obstruction of the first mentioned gas burner outlet openings operating to emit gas through said outlet port and said auxiliary burner flame operating to ignite said gas emitting from said outlet port, and the flames of said outlet port operating to ignite and destroy said link, said link, when destroyed, permitting closing of said valve.
- 55 6. In combination, a gas burner having a plurality of gas jet openings, an inlet pipe connecting said burner and a gas source and having a side port, a valve in said inlet pipe; a spring tending to close said valve; a link engaging said valve for holding the same open; an auxiliary burner mounted adjacent said gas burner and said link and having gas outlet ports therein communicating with a gas source, said auxiliary burner comprising a body having a horizontally extending flange for diverting ignited gas emitting therefrom, said auxiliary burner flames operating to ignite gas emitted from said side port when said first mentioned gas burner is obstructed, said last mentioned ignited gas operating to ignite and destroy said link to effect closing of said valve.
- 60 7. A device of the class described comprising a gas conduit terminating in gas jet openings and communicating with a gas source, said conduit having a side port, an auxiliary burner communicating with said conduit and having gas jet openings and normally ignited simultaneously with said gas jet openings; a valve in said inlet pipe; yieldable means tending to close said valve; combustible and inflammable means responsive to heat normally holding said valve open, obstruction of said conduit jet opening causing emission of gas from said side port, the ignited gas of said auxiliary burner operating to ignite gas emitted 120 from said side port to destroy said inflammable means to permit release and closing of said valve.
